(57) **CLAIM**

I claim the ornamental design of a mocktail fruit arrangement, substantially as shown and described.

DESCRIPTION

FIG. 1 is a front perspective view of a mocktail fruit arrangement in accordance with the present invention;
FIG. 2 is a front view of the mocktail fruit arrangement in FIG. 1;

FIG. 3 is a back view thereof;

FIG. 4 is a left side view thereof;

FIG. 5 is a right side view thereof;

FIG. 6 is a top view thereof; and,

FIG. 7 is a bottom view thereof.
